UNITED STATES PATENT OFFICE.

FRANK A. MAGEE, OF CHELSEA, AND ANDREW GARBUZZ, OF BOSTON,
ASSIGNORS TO THE MAGEE FURNACE COMPANY, OF BOSTON, MASS.

DESIGN FOR A HEATING-STOVE.

SPECIFICATION forming part of Design No. 16,876, dated August 24, 1886.

Application filed June 10, 1886. Serial No. 204,806. Term of patent 14 years.

To all whom it may concern:

Be it known that we, FRANK A. MAGEE, of Chelsea, and ANDREW GARBUZZ, of Boston, both in the county of Suffolk and State of Massachusetts, citizens of the United States, have invented and produced a new and original Design for Heating-Stoves, of which the following is a full, clear, and exact description, reference being had to the accompanying photographs, forming a part thereof, in explaining its nature.

The invention comprises a design for heating-stoves, the essential or material parts of which are, first, the general outline of the stove; second, the character or style of the ornamentation or finish; third, the open-work doors, including the front feed-doors, the side doors, and the door to the ash-pit chamber; fourth, the especial form or shape of the front of the stove immediately above and below the entrance to the combustion-chamber; fifth, the shape and ornamentation of the rail and of the brackets which attach it to the stove; sixth, the shape and ornamentation of the base of the stove and of the stove-legs; seventh, the shape of the top or upper section of the stove, and, eighth the panels and studies or pictures in relief upon each side of the lower section of the stove.

The photograph upon Sheet 1 is a front view 30 of the stove. The photograph upon Sheet 2 represents in perspective the front and one side of the stove. The photograph upon Sheet 3 represents in perspective the back and one side of the stove. The views on Sheet 4 show 35 the side panels.

The stove, it will be seen from the illustrations, is rectangular in cross-section, has a richly-ornamented outwardly-extending base-section, which projects outwardly upon all sides 40 of the stove, and an intermediate band upon the sides and back, which divides the main body of the stove into two sections, and an upper section or top, which is rectangular in shape, has rounded corners, inwardly-curved flaring sides and ends, is larger at its base than 45 at its top, and has a projecting border at the top. The stove also has rounded corners, and is very richly and profusely ornamented with a design which, while varying in some of its 50 details, is substantially uniform throughout the sides and back of the stove, and various de-

tails upon the front of the stove, in that the entire surface of these parts is ornamented with representations of leaves and fruit or flowers as upon the sides of the stove, and pine needles and cones as upon the back of the stove. All the doors of the stove have the same characteristics—that is, they are open-work doors, and they are profusely and richly ornamented and in harmony with the 5 ornamentation of the remainder of the stove. The panel study or picture A is well shown in the photograph on Sheet 4, and it comprises a study which we have called "Industry." It is a representation of a maiden at a spinning-wheel in the foreground, a window partially draped beyond, and a child holding a kitten. This picture or study is formed upon one of the side plates of the stove, and is surrounded by a border of leaves and flowers. The second 6 study or picture, A', is also well shown in one of the photographs upon Sheet 4. We have named it "Cinderella," and it represents that period in her life when her sisters are dressing for the ball and she is sitting by disconsolate. The study is also inclosed or surrounded by a circular panel richly ornamented with representations of fruit and leaves.

The two front doors, A, of the combustion-chamber are well represented in the photographs on Sheets 1 and 2, and each comprises two horizontal cross-bars, a vertical bar dividing the door into spaces for the reception of mica or other transparent lights. Griffins, dragons, or other similar mythological figures 8 are represented as supported by these bars, as interlaced with them, and holding them together.

Each of the side doors, B, is well shown in the photographs, and the essential features of each 9 are the curved edge of the upper inner corners of the door and the division of the door into spaces or openings of irregular shape by richly-ornamented bars bearing or having ornaments which harmonize with the characterizing ornamentation of its special side of the stove. The spaces within the door are adapted to receive mica or other transparent lights. The portion of the sides of the stove in which these doors are set are also well 10 shown in the photographs, and they are each richly ornamented with representations, in

one case of fruit and leaves and in the other case of leaves and flowers. They also have upper sections, comprising bar or scroll work of irregular shape, which form openings or apertures. This feature of the design is also well shown in the photographs.

The front section, C, of the stove is rounded or extended outwardly from the front of the stove, one part above the doors to the combustion-chamber, and the other part below said doors, and each part is provided with converging fluted lines or recesses. The upper part of the front section extends into the top section or part of the stove, and the lower part of the front section into the lower part, or to the hearth-plate.

The rail C extends across the front of the stove immediately above the hearth-plate, and is supported by a bracket at each end, which is highly ornamented with the prevailing features of the design. The rail and brackets are well shown in the photographs on Sheets 1 and 2.

The back D of the stove is well shown in the photograph on Sheet 3, and it is highly and profusely ornamented with a representation of pine needles and cones.

The general proportions and outline of the stove are well represented in the photographs on Sheets 1, 2, and 3.

The ornamentation of the top plate and the urn we consider do not form a material part of the design.

The front of the stove may be ornamented with tiles set in various places; but we consider that they do not form an essential feature of the design.

The door E of the ash-pit is made or composed of bars interlaced and highly ornamented, and it is well represented in the photographs on Sheet 1.

Having thus fully described my invention, I claim and desire to secure by Letters Patent of the United States—

1. In a design for a stove, the front door, comprising horizontal and vertical bars, spaces for mica or transparent lights, and griffins, dragons, or other mythological figures interlaced with the bars, as illustrated and described.

2. In a design for a heating-stove, the front section, C', rounded or extended outwardly from the front of the stove, provided with converging fluted lines or recesses, and disposed immediately above and below the opening to the combustion-chamber, as illustrated and described.

3. In a design for a heating-stove, the side door, B, composed of ornamented bars dividing the door into spaces or openings, and curved upon its upper edge, as illustrated and described.

4. In a design for a heating-stove, the side,

comprising a lower section or plate having a representation of fruit and leaves surrounding the circular panel, study, or border A, and an upper section separated from the lower section by a projecting plain-surfaced band, comprising a plate ornamented with fruit and flowers, having also scroll-work and spaces, and an open-work door with a rounded upper surface, as illustrated and described.

5. In a design for a heating-stove, the side of the stove, comprising a lower plate having a representation of flowers and leaves thereon in relief surrounding the circular panel A', an upper section separated from the lower section by a plain molding or band, and ornamented with flowers and leaves, and also having scroll-work and openings, and an open-work door having a rounded upper surface, as illustrated and described.

6. The herein-described design for a stove, the same comprising a base-section extending on all sides from the body of the stove and ornamented, with the plain body of the stove divided into two sections by a plain band or molding substantially rectangular in shape, the lower section having a panel, A, upon one side, and a panel, A', upon the other, each surrounded by a highly-ornamented border of flowers and leaves and fruit and leaves, the upper section having sides provided with the open-work door, scroll-work, and spaces above said door, and profusely ornamented with the characteristic ornamentation of the stove, the rounded front section and the door thereof, and the top arranged to project upon the front corners, sides, and back, as illustrated and described.

7. In a design for a heating-stove, a rail, C, rounded upon its front edge, and brackets ornamented with representations of leaves and arranged to project from the front corners of the stove, as illustrated and described.

8. In a design for a heating-stove, the back D, ornamented with a representation of pine needles and cones, as illustrated and described.

9. In a design for a heating-stove, a side section or plate, with a representation of fruit and leaves in relief thereon, and scroll-work, all arranged about the top and one side of the side door, substantially as illustrated and described.

10. In a design for a heating-stove, a stove base and legs rounded outwardly and ornamented with a representation of fruit and leaves, as illustrated and described.

Executed at Boston, Massachusetts, this 26th day of May, A. D. 1886.

FRANK A. MAGEE.
ANDREW GARBUTT.
